US00D914594S

(12) **United States Design Patent** (10) **Patent No.:** **US D914,594 S**
(45) **Date of Patent:** **** Mar. 30, 2021**

(54) **AUTOMATION DEMO CASE**

(71) Applicant: **Siemens Ltd., China**, Beijing (CN)

(72) Inventors: **Christoph Raum**, Amberg (DE); **Xiao Feng Zhou**, Beijing (CN)

(73) Assignee: **SIEMENS LTD., CHINA**, Beijing (CN)

(**) Term: **15 Years**

(21) Appl. No.: **29/672,731**

(22) Filed: **Dec. 7, 2018**

(30) **Foreign Application Priority Data**

Jun. 8, 2018 (CN) 201830289504.9

(51) **LOC (13) Cl.** **13-10**

(52) **U.S. Cl.**

USPC **D13/110**

(58) **Field of Classification Search**

USPC D13/110, 108, 118, 123, 162, 168, 169, D13/174, 177, 184, 199; D14/257, 432,

(57) **CLAIM**

The ornamental design for a automation demo case, as shown and described.

DESCRIPTION

FIG. 1 is a front view of a automation demo case, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a top, front and right side perspective view thereof; and,

FIG. 8 is a top, rear and left side perspective view thereof.

1 Claim, 8 Drawing Sheets
